UNITED STATES PATENT OFFICE

110,583

DESIGN FOR A THREAD DISPENSER

Charlotte Huber, New York, N. Y.

Application March 28, 1938, Serial No. 76,132

Term of patent 7 years

To all whom it may concern:

Be it known that I, Charlotte Huber, a citizen of the United States and resident of New York city, in the county and State of New York, have invented a new, original, and ornamental Design for a Thread Dispenser, of which the following is a specification, reference being had to the accompanying drawing forming part thereof, in which

Fig. 1 is a perspective view of the dispenser showing my design; and

Fig. 2 is a bottom plan view thereof.

The bird motif decoration shown is in different colors and in contrast to the color of the body of the dispenser as indicated by the color lining on the drawing.

I claim:

The ornamental design for a thread dispenser, as shown and described.

CHARLOTTE HUBER.
